UNITED STATES PATENT OFFICE

CHARLES L. GRIGG, OF ST. LOUIS, MISSOURI, ASSIGNOR TO THE HOWDY COMPANY, OF ST. LOUIS, MISSOURI, A CORPORATION OF MISSOURI

DESIGN FOR A BOTTLE

Application filed October 12, 1927. Serial No. 23,727. Term of patent 7 years.

To all whom it may concern:

Be it known that I, CHARLES L. GRIGG, a citizen of the United States, residing at 4012 Juniata Ave., in the city of St. Louis, State of Missouri, have invented a new, original, and ornamental Design for Bottles, of which the following is a specification, reference being had to the accompanying drawings, forming part thereof.

In the drawings:

Fig. 1 is a perspective view of a bottle showing my new design.

Fig. 2 is a like view of a bottle rotated 90 degrees showing my new design.

I claim:

The ornamental design for a bottle, as shown.

CHARLES L. GRIGG.
